FASTENING DEVICE

Samuel Segal, Brooklyn, N. Y., assignor of twenty-five percent to Charles Palmer, Washington, D. C., twenty-five percent to Harry Model and twenty-five percent to Harry Schwartz, both of New York, N. Y.

Application September 25, 1937, Serial No. 165,616

7 Claims. (Cl. 24—207)

The present invention is directed to an improved slide fastener of the type having a plurality of spaced runners attached to an elongated flexible and foldable ribbon adapted to serve as a closure for a gap defined by beaded edges of spaced flexible tapes usually attached to a garment although not necessarily limited thereto and for slidably guiding the plurality of runners. The dominating object of the invention is to provide a slide fastener of the type referred to wherein the runners are secured to the flexible closure by means retained in such relation to preclude injury to the wearer of the garment or to the garment. The invention has as another object the provision of a slide fastener wherein the several runners are slotted to receive loops adapted to be formed in the flexible closure and wherein the loops are retained in position within the runners by anchoring means spaced from the rear faces of runners and inaccessible to cause injury to the wearer of the garment or to the garment.

Other objects, advantages, and features of the invention will be readily understood from the teachings of the following description considered in the light of the accompanying drawing wherein:

Fig. 1 is a broken and front view of the adjustable slide fastener according to my invention showing the gap, defined by beaded edges of a pair of spaced and flexible tapes, in a closed relation.

Fig. 2 is a vertical sectional view taken on the line 2—2 of Fig. 1.

Fig. 2a is a fragmentary sectional view of the fastener showing the runners brought together to reduce the overall length of the flexible closure for opening the gap defined by the beaded edges.

Fig. 3 is a transverse sectional view on the line 3—3 of Fig. 1.

Fig. 4 is a perspective view of one of the runners illustrated in Fig. 1.

Fig. 5 is a fragmentary and broken view of another form of slide fastener according to the invention.

Fig. 6 is a transverse sectional view taken on the line 6—6 of Fig. 5.

Fig. 7 is a perspective view of one of the runners illustrated in Fig. 5.

Fig. 8 is a sectional view taken on the line 8—8 of Fig. 5 and

Fig. 9 is a rear fragmentary and broken view of another modified slide fastener according to my invention.

In the drawing, the slide fastener is generally

denoted 10 and includes spaced flexible tapes 11, a flexible closure 12 in the form of a ribbon and the plurality of spaced runners 13. Tapes 11 are adapted to be secured to the sides of a gap in a garment or wearing apparel (not shown) and are each provided with a beaded edge 14 adapted to be threaded into spaced enlarged longitudinally disposed channels 15 of the runners to slidably support, retain, and guide the latter. The several runners, however, are fixedly fastened but in spaced relation to the flexible ribbon 12 arranged at the back of the runners. Particularly however the several runners or blocks in the form according to Figs. 1 to 4 inclusive each include a slot 16 extending across the width thereof and in which a bend or loop 17 of the flexible ribbon closure is received and each of these runners is also provided with an opening 18 extending lengthwise of the runner and at right angles to and intersecting the loop receiving slot 16.

In actual practice, a portion of the closure ribbon 12 is inserted into slot 16 to form a loop 17 therein by suitable means not shown. Thereafter, anchoring means in the form of a pin 20 is forced into the longitudinal opening 18 to pierce and penetrate the formed loop 17 and be totally arranged within its runner as shown in Fig. 2. By this arrangement, the several runners 13 are fixedly fastened in spaced relation on the flexible ribbon 12 and longitudinally thereof. Subsequently the runners are slidably threaded on the beaded edges 14 of the flexible tapes.

The gap defined by the spaced beaded edges 14 may be readily closed or opened by actuating the end runner, for example, the runner having the swingable manipulator 24 attached thereto. As shown in Figs. 1 to 3 inclusive the flexible ribbon 12 is at the back of the beaded edges 14 and is extended to constitute a closure for the gap defined by these beaded edges.

When it is desired to open the gap the runner carrying the swingable manipulator 24 is urged in the direction indicated by the arrow 25, thus the several runners are slidably guided on the beaded edges 14 and carry with them ribbon 12 which becomes folded and shortened as indicated in Fig. 2a. In such relation the runners are at one end of the slide fastener and the gap between the beaded edges is open.

To close the gap, the swingable manipulator 24 is moved in a direction counter to the arrow 25, thereby extending the closure ribbon 12 along the entire length of the gap to widely separate the runners which are frictionally held in a set position by the beaded edges 14.

In case of the form illustrated in Figs. 5 to 8 inclusive, the several loops 17 adapted to be formed in the flexible ribbon 12 are each also inserted into a slot 16 extending widthwise along a respective slidable runner and thereafter an elongated pin 20 is inserted in the eye of a loop 17. The ends of pin 20 are subsequently turned to form terminals 21 which are moved into and firmly retained in the side grooves or sockets 22 to form a U shaped anchoring member as shown in Fig. 5 wherein terminals 21 extend in the same direction while the form according to Fig. 9 the anchoring pin 20 has its terminals 21 turned in an opposite direction but firmly retained or locked in the side sockets 22.

In each of the embodiments herein disclosed, the ribbon anchoring means is arranged in spaced relation to the rear face 23 of its runner and hence in use it cannot interfere or interlock with the undergarment of the wearer or chafe the skin of the user in case where the ribbon is not within close proximity to the undergarment although it is essential to the herein disclosed slide fastener according to the invention that the flexible ribbon 12 be of such width as illustrated to constitute closure means for the gap defined by the beaded edges 14 when the ribbon is extended as shown for example in Fig. 1.

While the invention has been described in detail and reference has been made to specific applications thereof, it is to be understood that the invention herein disclosed is not limited to such specific applications and it is intended that all matter contained in the above description or shown in the accompanying drawing shall be interpreted as illustrative and not in a limiting sense.

I claim:

1. In a fastener comprising spaced tapes having beaded edges defining an elongated gap, a plurality of runners each including grooves having walls slidably guided by said edges and lengthwise of said gap and each including a slot extending widthwise of said gap and an opening extending substantially normal to said slot and in communication therewith, a foldable and flexible ribbon shiftable lengthwise of said gap and disposed at the rear of said edges and comprising a plurality of loops disposed in said slots, and pin means disposed within said openings and passing through said slots for securing said loops to said runners.

2. In a fastener comprising spaced tapes having beaded edges defining an elongated gap, a plurality of spaced runners shiftable lengthwise of said gap and slidably guided by said edges and each including a slot extending widthwise of said gap and an opening substantially normal to said slot and in communication therewith, a flexible closure ribbon shiftable lengthwise of said gap and disposed at the rear of said edges and having a plurality of spaced loops disposed at least in part within said slots, and anchoring means within said openings and passing through said slots and cooperating with said loops for securing said runners to said ribbon.

3. In a fastener comprising spaced tapes having beaded edges defining an elongated gap, a plurality of spaced runners each having grooved

sides slidably guided by said edges and lengthwise of said gap and each including a slot disposed widthwise of said gap and an opening extending longitudinally thereof and communicating with its respective slot, a flexible ribbon disposed lengthwise of said gap and at the rear of said edges and having a plurality of spaced loops extending widthwise of said ribbon and disposed at least in part in said slots, and pin means disposed within said openings and passing through said slots and spaced from front and rear faces of a respective runner and cooperating with said loops for holding said runners to said ribbon.

4. In a fastener comprising spaced tapes having beaded edges defining an elongated gap, a plurality of spaced runners each having grooved sides slidably guided by said edges and lengthwise of said gap and each including a slot disposed widthwise thereof and a longitudinally disposed opening in communication with its respective slot, a closure for said gap comprising a flexible and foldable elongated ribbon having a plurality of spaced loops disposed at least in part widthwise thereof and arranged at least in part in said slots, and pin means within said openings and passing through said slots for penetrating said loops for securing said runners to said ribbon.

5. In a fastener comprising spaced tapes having beaded edges defining an elongated gap, a runner having spaced grooves comprising walls slidably guided by said edges longitudinally of said gap and including a slot and an opening disposed substantially normal to said slot and in communication therewith, a closure for said gap comprising an elongated flexible ribbon having a loop disposed at least in part within said slot, and pin means within said opening and passing through said slot for penetrating said loop for securing said ribbon to said runner.

6. In a fastener comprising spaced tapes having beaded edges defining an elongated gap, a plurality of runners having spaced grooves having walls slidably guided by said edges longitudinally of said gap and each including a slot extending widthwise of said gap and an opening in communication with said slot and extending longitudinally of said gap, and an elongated closure for said gap comprising a flexible ribbon having a plurality of loops at least in part disposed in said slots, and anchoring means arranged in each of said openings and penetrating adjacent and opposed sides of said loops for holding said ribbon to said runners.

7. In a fastener comprising spaced tapes having beaded edges defining an elongated gap, a runner having spaced and grooved sides slidably guided by said edges longitudinally of said gap and including a slot extending widthwise of said gap and having an opening in communication with said slot and disposed longitudinally of said runner, a foldable closure ribbon for said gap comprising loop means disposed at least in part within said slot, and pin means within said opening and cooperating with said loop means for holding said ribbon to said runner.

SAMUEL SEGAL.
